(57) **CLAIM**

The ornamental design for a belt buckle, as shown and described.

DESCRIPTION

FIG. 1 is a perspective view of a belt buckle showing my new design;

FIG. 2 is a top view thereof;

FIG. 3 is a bottom view thereof;

FIG. 4 is a front view thereof;

FIG. 5 is a back view thereof;

FIG. 6 is a left side view thereof, with the right side view being a mirror image thereof; and,

FIG. 7 is a perspective view thereof shown in an environment of use with straps in broken lines.

The broken lines in FIGS. 7 depict environmental structures around the belt buckle and form no part of the claimed invention. pg.2
